UNITED STATES PATENT OFFICE

ARTHUR E. BROUGHTON, OF MINNEAPOLIS, MINNESOTA, ASSIGNOR TO BROUGHTON COMPANY, A CORPORATION OF SOUTH DAKOTA

CLEANER ATTACHMENT FOR PAPER DRIERS

Application filed October 19, 1928. Serial No. 313,478.

This invention relates to a device of the type described in my application for patent on cleaners for paper driers, filed June 2, 1928, Serial No. 282,411, whereby particles of 5 sizing, fibre and the like may be removed from the revolving rolls of paper drying machinery.

In the cleaner of this application a scraper is applied to the periphery of the paper drier to be cleaned and the particles loosened by the scraper are conducted away from the machine by air in a suitable conduit. When, as sometimes occurs, the moist paper web breaks in the operation of the drier, the free end 10 tends to wind itself upon the drier and passes into the air conduit of the cleaner where it collects in a mass which must be removed. The present invention relates particularly to the means for preventing serious clogging 15 of the cleaner and for removing from the conduit the portions of the broken web.

It is my object to provide simple and efficient means whereby an operator may quickly and easily remove portions of the broken 20 paper web from the air conduit or hood extending along the drier roll. Other objects will appear and be more fully pointed out in the following specification and claims.

In the drawings Figure 1 is a plan view 25 of my improved cleaning attachment mounted upon a paper drier of common type, fragmentary portions of the drier and frame being shown; Fig. 2 is a transverse section taken on the line 2—2 of Fig. 1; Fig. 3 is a 30 fragmentary longitudinal section through the cleaner hood, showing the web removing device and Fig. 4 is a detailed sectional view taken on the line 4—4 of Fig. 1.

In the drawings the numeral 5 indicates 35 a cylindrical paper drier of common type which is revolvably supported at its ends upon frame members 6. The cleaning mechanism comprises a blade 7 of flexible steel extending longitudinally in contact with the periphery 40 of the drier as described in my co-pending application above identified.

Along one edge the casting 8 is pivotally supported upon a shaft 9 which projects at 45 its ends above the frame members 6 and has 50 bearings 10 supported thereon.

Upon the inclined upper surface of the casting 8 is mounted a hood 11 for collecting the particles scraped from the drier 5 by the blade 7. This hood 11 is partially closed at one end by a door 12 and its opposite end 55 communicates with a large air suction pipe 13. A suitable fan (not shown) is provided for creating suction in the pipe 13 and hood 11. The hood 11 is open at the bottom and its edge 14 (Fig. 2) extends closely adjacent 60 to the periphery of the drier 5. The opposite longitudinal edge of the hood 11 is fixed upon a tubular shaft 15 which is arranged to swivel in bearings 16 secured to the top of the casting 8. Thus the hood 11 65 is arranged to be swung to an open position as indicated in dotted lines in Fig. 2. The bearings 16 pass through slots 18 in the edge of hood 11.

Within the hollow bore of the shaft 15 is 70 mounted a rod 19, having a handle 20 on one end. The other end of the rod 19 has rigidly secured thereto a plate 21 which projects radially out through a longitudinal slot 22 in the shaft 15. The plate 21 is bent upward along the inner surface of the hood 11 75 as indicated at 23 in Fig. 2 and its free edge is slotted to form a series of fingers 24 and 25. These fingers are preferably formed with wedge shaped front surfaces as indicated in Fig. 3 and they are bent laterally to project at different angles within the hood 11 as shown in Fig. 2. To facilitate moving the hood 11 to open position, I provide a crank or lever 26, having a pair of jaws 80 27 (Fig. 4) adapted to grip flattened surfaces 28 upon an accessible end of the shaft 15.

In operation the fingers 24 and 25 are normally retained in the end of the hood 11 adjacent to the air pipe 13, as indicated in Figs. 1 and 2. With the hood 11 closed and the blade 7 resting upon the periphery of the drier 5, the cleaner operates to remove particles from the periphery of the drier roll 90 and to immediately conduct them away from the machine through the hood 11 and pipe 13, as is more particularly described and claimed in my co-pending application above identified. When a brake in the web occurs 95 100

adjacent to the drier 5 there is a tendency for the loose end of the web to wind itself upon the drier 5 but it is stripped from the drier by the blade 7 and caused to pass into the hood 11. The rapidly rotating drier sometimes delivers a large amount of the broken web into the hood 11 with considerable force and it will be evident in the absence of efficient means to guard the entrance to the suction pipe 13 said pipe would rapidly become clogged. By my arrangement of the fingers 24 and 25, pieces of objectionable size are prevented from entering pipe 13 and when the paper web collects in the hood 11 it may be quickly and easily removed by operating the rod 19 to draw the fingers 24 and 25 longitudinally through the hood. Thus the handle 20 may be grasped by the operator and, after opening the door 12 upon the adjacent end of the hood 11, the fingers 24 and 25 may be drawn from one end of the hood 11 to the other, as indicated in dotted lines in Fig. 3. The sloping front edges of the fingers 24 and 25 forcibly expel the obstructing portions of the web from the hood. When the hood becomes badly clogged, it is sometimes necessary to move it to open position, indicated in dotted lines in Fig. 2, before drawing the fingers 24 and 25 longitudinally through the hood. The hood is designed to be raised easily to open position and in practice, when a brake occurs in the web at a certain point, the web is delivered into the hood with sufficient force to raise it to open position. The operator, having removed the broken pieces of web from the hood 11, can quickly return the device to operative position by thrusting the rod 19 back into the hollow shaft 15 and by closing the hood 11, if it has been opened.

Having described my invention what I claim as new and desire to protect by Letters Patent is:

1. In a cleaner attachment for a paper drying roll, an air conduit extending longitudinally adjacent to the periphery of said roll to receive particles of foreign matter, said conduit being formed to confine a blast of air for removing said particles therefrom and means movable longitudinally in said conduit for expelling broken pieces of the paper web from said conduit.

2. In a cleaner attachment for a paper drying roll, an air conduit extending longitudinally adjacent to the periphery of said roll to receive and remove particles of foreign matter therefrom, said conduit having an outlet near one end and means movable longitudinally in said conduit for expelling broken pieces of the paper web from said conduit, said means being normally located near the outlet of said conduit to arrest broken pieces of the web.

3. In a cleaner attachment for a paper drying roll, an air conduit extending longitudi-

nally adjacent to the periphery of said roll to receive and remove particles of foreign matter therefrom, means movable longitudinally in said conduit for expelling broken pieces of the paper web from said conduit, said means being normally positioned near one end of said conduit and a rod extending parallel to said conduit and connected to said means for moving the same longitudinally through said conduit.

4. In a cleaner attachment for a paper drier, a scraper extending longitudinally in engagement with the periphery of a drying roll for removing foreign matter from the peripheral surface of said roll, a hood arranged along said scraper to receive the particles loosened thereby, members extending transversely within said hood to arrest pieces of broken paper web and means for moving said members longitudinally within said hood to expel the broken paper web therefrom.

5. In a cleaner attachment for a paper drier a conduit extending longitudinally adjacent to the periphery of a drying roll for removing foreign matter from the peripheral surface of said roll, said conduit having an outlet at one end, a plurality of members extending transversely within said hood to arrest pieces of broken paper web near said outlet and means for moving said fingers longitudinally within said hood to expel the broken paper web therefrom, the front surfaces of said members extending obliquely rearward to loosen the web by wedge action.

6. In a cleaner attachment for a paper drier, a scraper extending longitudinally in engagement with the periphery of a drying roll for removing foreign matter from the peripheral surface of said roll, a hood arranged along said scraper to receive the particles loosened thereby, a tubular member along one edge of said hood, a plurality of fingers extending transversely within said hood to arrest pieces of broken paper web and a rod slideable in said tubular member for moving said fingers longitudinally within said hood to expel the broken paper web therefrom.

In testimony whereof, I have hereunto signed my name to this specification.

ARTHUR E. BROUGHTON.
